UNITED STATES PATENT OFFICE.

MICHEL DAVID, OF JEMEPE SUR MEUSE, BELGIUM.

GRINDING AND MIXING APPARATUS.

Application filed September 28, 1925, Serial No. 59,202, and in Belgium October 2, 1924.

The present invention has for its object a grinding and mixing apparatus serving for the preparation of mortar of any composition, this apparatus being also capable of serving as a grinding machine proper, for the treatment of other materials, as for instance coals, lime or chalk, moulding sand, ceramic material, and the like, and its advantage relatively to other apparatus of this kind and particularly in comparison with crushing mills with vertical rollers, resides in its permitting to reduce said materials to a most tenuous powdery and mixed state in a much more economic manner.

According to the present invention; the grinding and mixing apparatus comprises essentially a horizontal cylindrical jacket the inner face of which, or part of it, cooperates with cone shaped or cylindrical suitably, profiled rollers which are controlled by a driving shaft, the longitudinal axis of which coincides or nearly coincides with the longitudinal axis of said cylinder, this system being eventually completed by scrapers 25 suitably disposed at the loading and discharge ends of said cylinder, and series of adjustable scrapers between said rollers, all these scrapers participating with the rotary movement of said rollers as a unit.

The annexed drawings represent by way of example two different constructions of said apparatus.

Figure 1 represents a side view of the apparatus partly in section taken along the line AB Figure 2.

Figure 2 represents a transverse section in the apparatus taken along the line CD EF, Figure 1, the sectional view along CD being seen in the direction of the arrow *w*, and that along EF in the direction of the arrow *y*.

Figures 3^a 3^b, 3^c represent the different rollers used in the apparatus according Figures 1 and 2.

Figure 4 represents a transverse section along AB Figure 5 in a modified construction of the apparatus.

Figure 5 represents a longitudinal section along CD Figure 4, the roller being however not shown in this figure.

Figure 6 represents a series of scrapers as used in the apparatus according to Figures 4 and 5.

Figures 7^a, 7^b, and 8 represent rollers of different constructions which may be used within the apparatus according to the present invention.

According to Figures 1, 2, 3^a, 3^b, 3^c the improved grinding and mixing apparatus comprises a cylindrical jacket composed of the upper part 1 and lower part 2 assembled by bolts 3 and forming a front wall 4 and a rear wall 5, which form in their turn bearings 6 and 7 within which is mounted the driving shaft 8 provided with a pulley 9 disposed preferably at the rear end of the apparatus. The front wall 4 is formed with one or more openings 10 permitting to look after and to lubricate the inner movable parts of the machine, whereas the rear wall 5 is entirely open at 11 for the same and other purposes, the latter of which will be described afterwards.

Within the interior of the lower part 2 of the jacket is fixed a false-bottom 12 of especially resistant material, as it is at this part of the jacket, that the principal grinding and mixing action takes place.

Upon the shaft 8 are keyed or otherwise rigidly fixed a front cross or equivalent plate 13 and a rear equivalent plate 14. Each of these plates is provided with four or any other suitable number of radial slots 16 the opposite sides of each slot being provided with grooves 37. Each of these slots 16 serves to receive a squareshaped sliding block 35 having lateral cylindrical extensions 36 which are slidably engaged within said grooves 37. A pair of corresponding sliding blocks 35 within the plates 13, 14 constitute the bearings for a corresponding number of shafts 17 upon which are mounted the grinding and mixing rollers 18. It is preferable to give the middle part of each of shafts 17, upon which is seated the corresponding roller, a square section, only the end portions of said shafts being of cylindrical section, to permit said shafts to freely rotate within the bearings 35, these bearings serving simultaneously to guide the shafts 17 radially within the plates 13, 14. The particular construction of the guide blocks 35, 36 and their disposition within the grooved slots 16, 37 efficiently avoids jamming of the shafts 17 as well with respect to the rotary movement as with respect to the radial movement of these latter within plates 13, 14.

In the example shown in the drawings there are four shafts 17, and upon these shafts are fixed in any suitable manner four rollers 18. According to Figures 1, 2, 3^a, 3^b, 3^c, these rollers are as follows:

(1) Two of them are of identically the

same configuration and are constructed as represented in Figure 3^a, that is to say their front side portion is provided with a right-handed thread of considerable depth and decreasing towards the rear side, this thread occupying approximately one half, of the total length of the roller, whereas their rear side half or portion presents a flat peripheral surface.

10 (2) The third roller (Figure 3^b) is provided through nearly one half of its length and upon its front side portion with parallel circular grooves (no thread) whereas its rear side portion has a flat peripheral surface.

15 (3) The fourth roller (Figure 3^c) is provided through nearly one half of its length and upon its front side portion with a flat peripheral surface, whereas its rear side portion is provided with a left-handed thread, the characteristics of which are contrary to that of the threads of the first mentioned runners.

20 All these runners are of the same dimensions and are of slightly conical section diverging towards the front side of the device.

25 The shaft 8, when considered in the sense of arrow α (Fig. 1) turns in a clockwise sense.

30 The jacket-part 1 is provided at its lowest front-side right-hand portion (arrow α) with a loading-hopper 22, a spray cone or sprinkler 23 with regulating cock 24 being disposed for instance within said hopper opposite to the loading orifice.

35 According to Figures 1 and 2 the rear side portion of jacket 1, 2, 5, open at 11, forms an enlarged hollow portion 29, serving to receive a ring conveyer 27, 28 bolted to projections 26 of the rear plate 14. The ring conveyer 27, 28 cooperates with a sleeve conveyer 31, passing from the outside through an opening 30 in part 29 of the jacket, into 40 said ring-conveyor 27, 28, and having a suitably shaped beveled end portion, which comes into contact with the inner face of part 28 of the ring conveyer 27, and which is directed in a sense opposite to the direction of rotation of the device.

45 The operation is as follows:

50 The rough materials to be treated, are delivered in any convenient manner to the hopper 22 and are drawn within the interior of the device by the threaded portions of the first mentioned rollers 18. These threaded portions produce a preliminary and progressive disintegration and mixing of the materials, carrying them simultaneously towards the rear end of the device, thereby obliging them to enter within the path of the flat shaped portions of said rollers, where the materials are definitely reduced to the desired state, the disintegrating action of the 55 rollers being highly increased by the tor-

sional action they produce due to their conical section. At the same time water is delivered under pressure through sprinkler 23, to give the mass or material in treatment the desired degree of moisture.

60 The action of the second mentioned roller is essentially the same as that of the first mentioned rollers, with the difference that this roller, having no thread-shaped grooves, will not displace the materials towards the 65 end portion of the device.

65 The third mentioned roller serves to retard the displacement of the materials towards the rear end of the device, due to its left handed threaded endside portion, so 70 obliging those parts of the material which are not yet sufficiently crushed and mixed, to be entirely disintegrated and mixed by the whole roller system.

75 As the materials treated as above pass 80 from the front to the rear end of the device, they are finally delivered at 25 (Figure 1) within the ring conveyer 27, 28 and are from here automatically directed to the outside through the sleeve conveyer 31.

80 The device described may be completed by a suitable system of scrapers as show in Figures 4, 5 and 6, this depending principally from the nature of the materials to be treated.

85 According to Figures 4, 5 and 6, the front side plate 13 is provided with one or more scraper plates 33 serving to wipe off the materials entering from the hopper 22, to the interior of the device, propelling them 90 simultaneously beneath the front side ends of the runners.

95 Moreover, series of scraper plates may extend from the front side plate 13 to the rear side plate 14, between two successive 105 rollers. Such series of scraper plates 44 (see Figures 5 and 6) may be each pivotably connected, on the one hand, to a rod 42 which is rigidly secured to plates 13, 14, and on the other hand, to a rod 43 which is secured 110 to plates 13, 14 in such a manner as to permit of being adjusted in its longitudinal sense, for instance by suitably fastening the nuts 46 upon the threaded extremities of said rod 43. The plates 44 are inclined in 115 such a manner as to cause the materials to be treated to advance from the front side to the rear side of the device. By more or less inclining the scraper plates 44 in the mentioned direction, the material in treatment 120 will advance with a greater or less speed, whereby the rate of its disintegration and mixing may be controlled at will.

125 If the given material, for instance moulding sand, is to be treated at a more or less dry state, certain of the rollers 18 or all of them may be substituted by rollers according to Figures 7^a and 7^b, composed of two discs or cylindrical portions 18^a with trunnions 19^a and of longitudinal crushing bars 18^b 130

or 18° of circular, ovoidal or other suitable cross-section, which are rigidly secured to said discs.

If the material to be treated is desired to advance with more or less rapidity from the front to the rear end of the machine, certain of the rollers 18 or 18a, b, c or all of them are substituted by rollers 18d (see Figure 8) having only parallel grooves of sufficient depth and width.

According to Figures 4 and 5, the rear plate 5 of the jacket is closed and there is a lateral downwardly inclined conduit 40 for the discharge of the treated material. For this purpose the rear side rotary plate 14 is also provided with one or more scrapers 38, which take with them the treated material pressed out from the path of the rollers, and cause said material to pass into conduit 40 from which it is directed outside, such discharge being assisted by centrifugal force and also by the pressure of the advancing material.

The plate 5 may be provided with a supplementary closable orifice 11 for discharge, which normally remains closed.

It is evident that the device described may be modified in many respects without departing from the scope of the present invention.

What I claim is:

1. In an apparatus for the purpose set forth, the combination comprising a stationary cylindrical jacket, means for supplying material to be treated thereto, means for discharging treated material therefrom, and means cooperating with said jacket, said means comprising a plurality of rollers, one of said rollers having a helical groove extending from its feed end toward its discharge end and decreasing in depth from feed end toward discharge end and having a portion adjacent the discharge end of smooth conical shape, another of said rollers being of similar construction but its grooved and smooth portions being reversed in position and the direction of its helical groove the reverse of that of the first mentioned roller so that the action of the one in the axial movement of the material being treated will be opposed by the action of the other, and another roller having an annularly grooved portion and a smooth conical portion, its grooved portion being adjacent the feed end of the jacket and formed with a plurality of annular grooves decreasing in depth toward the smooth portion, said grooved portion serving to progressively crush the material being treated without moving it axially.

2. In an apparatus for the purpose set forth, the combination comprising a stationary cylindrical jacket, means for supplying material to be treated thereto, means for discharging treated material therefrom, and

means cooperating with said jacket and comprising a plurality of rollers, one of said rollers having a helical groove extending from its front toward its rear and decreasing in depth progressively in the same direction the said roller having a smooth conical portion to the rear of said grooved portion, and another of said rollers being of similar construction but its slotted and smooth portions being reversed in position and the direction of its helical groove the reverse of that of the first mentioned roller so that the action of the one roller in the axial movement of the material being treated will be opposed by the action of the other.

3. In an apparatus for the purpose set forth, the combination comprising a stationary cylindrical jacket divided into an upper and a lower portion, the upper portion being provided laterally at one end with a feeding hopper, a fluid supply means arranged to discharge, at will, fluid into the interior of said jacket at a point adjacent the said hopper, operative means disposed in said jacket and comprising a plurality of rollers, each having a portion provided with a longitudinally extending helical groove and a smooth portion adjacent said grooved portion, and a roller having a portion provided with a plurality of annular grooves and a smooth portion adjacent said grooved portion, scraper plates mounted to rotate with said rollers about a common axis as a unit, said feeding hopper discharging the material to be treated laterally into the path of said scraper plates and the corresponding end portions of said rollers, a hollow ring rotating with said rollers and receiving the treated material from the discharge ends thereof, and a discharge sleeve extending through said jacket and having an open end projecting into said ring closely adjacent the peripheral wall thereof to scrape the treated material therefrom into said discharge sleeve.

4. In an apparatus for the purpose set forth, the combination comprising a stationary cylindrical jacket, means for supplying material to be treated thereto, comminuting means operatively disposed in and cooperating with said jacket and receiving the material to be treated at one end and discharging the treated material at the other end inside of said jacket, a hollow ring disposed in said jacket adjacent the discharge end of said comminuting means and receiving the material therefrom as treated, means for rotating said ring, and a discharge sleeve extending through said jacket and projecting into said hollow ring adjacent the peripheral face thereof to scrape the treated material therefrom into said discharge sleeve.

5. In an apparatus for the purpose set forth, a stationary cylindrical jacket, and

- means disposed within and cooperating with said jacket and comprising, in combination, disintegrating rollers of which at least one is provided around a portion of its working 5 face with a helical groove and of which another is provided around a portion of its working face with a plurality of annular grooves.
6. In an apparatus for the purpose set forth, the combination comprising a stationary jacket, and disintegrating means disposed within and cooperating with said jacket and comprising rollers of which at least one is provided around its working face with a helical groove and of which another is formed around its working face with a plurality of annular grooves.
7. In an apparatus for the purpose set forth, the combination comprising a stationary cylindrical jacket, and disintegrating means disposed within and cooperating with said jacket and comprising rollers of which at least one is formed with a helical groove around a portion of its working face, and of which another is formed around a portion of its working face with a plurality of annular grooves, each of said rollers being of conical 25 form.
8. In an apparatus for the purpose set forth, a stationary cylindrical jacket divided 30 into an upper, and a lower, portion, the upper portion being provided laterally at one end with a feeding hopper, and a fluid supply means arranged to discharge, at will, fluid into the interior of said jacket at a point adjacent the said hopper, in combination with operative means disposed in and cooperating with said jacket and comprising disintegrating rollers of which at least one is provided around a portion of its working face with a 35 helical groove, and of which another is formed around a portion of its working face with a plurality of annular grooves, and scraper units comprising each a plurality of adjustable plates, said units each being mounted to rotate with said rollers about a common axis as a unit, said feeding hopper discharging the material to be treated laterally into the path of the corresponding end portions of said rollers and of the corresponding scraper plates.
